A. T. PALMER

RAIL ANTICREEPER

Filed April 27, 1925

FIG. 1

FIG. 2

FIG. 3

FIG. 4

INVENTOR:
Alphonso T. Palmer
By Nissen & Crane
ATTYS.

UNITED STATES PATENT OFFICE.

ALPHONSO T. PALMER, OF CHICAGO, ILLINOIS.

RAIL ANTICREEPER.

Application filed April 27, 1925. Serial No. 26,185.

My invention relates to rail anchoring devices for railway rails and has for one of its objects the provision of simple and efficient means for effectively holding rails, and the 5 like, from longitudinal movement.

A further object of my invention is the provision of a clamping device having a lever, wedge, and torque action produced by one and the same adjustable tightening 10 means.

Another object of my invention is the provision of a rail anchoring device that is adapted to hold the rail plate in its proper position.

15 A still further object of my invention is the provision of means for anchoring a rail in place that are adapted to be effective in restraining the backward thrust of the rail as well as the forward thrust thereof.

20 Another object of my invention is the provision of the device which can be easily applied to a rail with comparatively little cost in labor.

25 A further object of my invention is the provision of a rail anchoring device that may be tightened periodically to compensate for the elasticity and wear of the parts thereof.

Other objects will appear hereinafter, the 30 novel features and combinations being clearly set forth in the appended claims.

In the drawings:

Fig. 1 is a horizontal plan view of a fragmental section of the tie and rail showing my improved anchoring device secured 35 thereto;

Fig. 2 is a fragmental sectional view taken on line 2—2 and looking in the direction of the arrow;

Fig. 3 is a side elevation of a rail showing 40 my improved rail anti-creeper;

Fig. 4 is a cross-sectional view taken on line 4—4 of Fig. 3 and looking in the direction of the arrows; and

Fig. 5 is a fragmental sectional view showing 45 an exaggerated illustration of the relative tightened positions of several elements of the anchoring device.

Referring more particularly to the drawings it will be seen in Fig. 4 that the anchoring device comprises a metal gripping member 1, preferably of cast iron having a flat outer side 2 and an inner side having a groove 3 extending longitudinally of its length. The groove 3 is provided to receive the edge portion 4 of the flange of a rail 5. This groove 3 has a flat lower surface 6 and

an inclined upper wall 7, the upper wall 7 being inclined sufficiently to the parallel with the inclined upper surface of the flange of the rail 5. The groove 3 is of such size as to provide a tight wedging grip on the edge portion 4 of the flange when the metal member is secured thereon.

In Figs. 1, 2 and 3 the anchoring device is shown secured to the rail 5 which is mounted on a tie 8, there being a rail plate 9 disposed between the rail and tie. The metal side member 1 is disclosed as being substantially longer than it is wide and provided with a flange 10 through which an opening 11 passes. This opening is rectangular in cross-section as shown in Fig. 1 and is for the purpose of receiving a rail spike 12. The flange 10 is located adjacent the inner end of the side member 1 and the opening 11 therein is in registration with an opening 13 in the rail plate 9. The spike 12 passes through both of these openings and into the tie 8, thus securing the flange-engaging side member 1, the rail plate 9 and the tie 8 in a fixed relation. The outer end or the end of the flange-engaging member which is spaced apart from the tie, is disclosed as being enlarged and having an opening therethrough to receive a hook-bolt 14. A shoulder 15 is provided on the grooved gripping member 1 at the point where the enlargement commences. This shoulder abuts against the edge 16 of the rail plate 9 for reasons herein-after disclosed.

The hook-bolt 14 is shown in Figs. 1 and 4 to be disposed beneath the rail flange and adjacent the lowermost surface 17 thereof. This bolt is threaded at one end to receive a nut 18 and is enlarged and disposed upwardly at the opposite end to form a hook 19. The hook 19 is formed to receive the lateral edge 21 of a flange of the rail 5 and is prolonged to extend slightly over the inclined upper surface 21 of the flange. It should be understood that the hook-bolt 14 lies adjacent the bottom surface 17 of the rail 5 and that said hook is slightly spaced apart from the lateral side 22 of the tie 8. This hook-bolt 14 is positioned in the space between the bottom surface of the rail and the bed of the road upon which the tie rests. When the bolt 14 is positioned as shown in the drawings and the nut 18 is tightened, the flange edge engaging member 1 is tightly wedged upon the edge portion 4 of the flange. When the nut 18 has been tightened sufficiently to

force the flange edge portion 4 completely within the groove 3, further tightening of the nut produces a leverage which tends to cause the flange edge-engaging member 1 to assume the position shown in Fig. 5, it being understood that the hook-bolt 14 is positioned below the groove 3 sufficiently to produce such a leverage action. This leverage action tends to pull downwardly on the two lateral flange edge portions 4 and 20 and to move the central portion of the bottom of the rail upwardly. Thus it should be understood that the anchoring device is clamped and secured tightly to the rail flange by means of a plurality of forces namely the direct wedging action of the edge portion 4 of the flange within the groove 3, the leverage due to the position of the hook-bolt 14 with respect to the groove 3 and the stress caused by such a leverage action which tends to draw the edge portions of the flange downwardly. It should be understood that the leverage action causes the edge portion 4 of the flange to be gripped by the upper and lower walls 7 and 6 respectively of the groove 3 with a force additional to the force caused by the wedging action.

All of the forces applied by the hook-bolt are for the purpose of clamping the anchoring device securely to the edge portion of the flange of a rail. With the device secured to the rail as illustrated and described the rail is restrained from longitudinal movement relative to the tie by means of the spike 12 and the shoulder 15. It is again pointed out that the shoulder 15 abuts against the edge 16 of the plate 9. The rail plate 9 is secured to the tie by the spike 12 and by an additional spike 23 positioned diametrically opposite from the spike 12. For this reason any movement of the rail to the left as viewed in Fig. 3 is arrested by the shoulder 15 which abuts against the edge of the rigidly secured rail plate 9. Movement of the rail in both directions is also arrested by the spike 12 which passes through the flange 10 of the gripping member 1 and through the rail plate 9.

When a train passes over the rails the latter tend to move in the direction of the train. This movement is called the forward movement of the rail and is due to vertical waving of the latter in advance of the train. Backward movement of the rail is also produced by the thrust of the wheels in the direction opposite to the direction of movement of the train. Both of these movements are effectively arrested by the anti-creeping device herein disclosed. The forward movement is by far the greater and is resisted by the spike 12 which secures the gripping member 1 directly to the tie and by the rail plate which is secured directly to the tie by spikes 12 and 23 and which abuts against the shoulder 15 of the gripping member 1.

Obviously those skilled in the art may make various changes in the details and arrangement of the parts without departing from the spirit and scope of the invention defined by the claims hereto appended, and it is therefore desired not to be restricted to the precise construction herein disclosed.

Having thus fully described and shown an embodiment of the invention what is desired to be secured by Letters Patent of the United States is:

1. In combination, a railway tie, a rail on said tie, a rail plate having openings therein, disposed between said tie and said rail, a rail spike securing said rail plate directly to said tie at one of said openings, a rail flange engaging bracket having an opening therethrough in registration with one of the openings in said rail plate, means securing said bracket and rail plate together and to said tie, and means for securing said bracket on the flange of said rail by a combination of wedge and leverage actions.

2. The combination with a railway rail, of a railway tie, a rail plate having an opening on one side and secured to said tie on the other side, a rail flange gripping bracket secured to the edge of the flange of said rail and to the rail plate at the opening therein to prevent movement of said rail in any direction relative to said tie, and a shoulder on said bracket for engaging the edge of said rail plate to further resist movement of the rail towards the tie.

3. A rail anchor comprising an elongated member having a flange extending along one side thereof for engaging the top surface of the edge of a rail flange, said member having a shoulder disposed below and spaced from said first-named flange at one end of said member to provide a groove for receiving said rail flange, said member having a downwardly projecting ear below said shoulder, said ear being perforated, a horizontally disposed holding member extending thru said perforated ear and having a hooked end for engaging the opposite edge of said rail flange, and a horizontally extending ear at the end of said elongated member opposite said perforated ear, said horizontally extending ear having an opening extending vertically therethrough for receiving a spike to hold said member in fixed position on a tie and in engagement with the edge of the rail flange.

4. In combination, a railway rail, a tie for supporting said rail, a tie plate interposed between said rail and tie, and a rail clamp for holding said rail in position on said tie and tie plate, said clamp comprising a horizontally disposed member having a flange provided with an inclined lower face for engaging the top face of the edge of a railway rail, a shoulder on said member disposed below said flange at one end of said member

and spaced therefrom to provide a groove for receiving the flange of the rail, a downwardly projecting ear on said member below said shoulder, said ear having a horizontal 5 perforation therethrough, a bolt extending through said perforation and having a hook for engaging the opposite edge of the rail flange, said ear having a shoulder thereon engaging the edge of said tie plate, a horizontally extending ear at the end of said 10 member opposite said first-mentioned ear

said horizontally extending ear having a perforation therethrough registering with the perforation in said tie plate, and a spike extending through said perforations embedded in said tie to hold said tie plate and holding member in fixed position on said tie. 15

In testimony whereof I have signed my name to this specification on this 25th day of April, A. D. 1925.

ALPHONSO T. PALMER.
